*Inventor,
John Kirby Jr.*

UNITED STATES PATENT OFFICE.

JOHN KIRBY, JR., OF DAYTON, OHIO, ASSIGNOR TO THE DAYTON MANUFACTURING COMPANY.

LAMP.

SPECIFICATION forming part of Letters Patent No. 354,910, dated December 28, 1886.

Application filed February 19, 1886. Serial No. 192,508. (No model.)

To all whom it may concern:

Be it known that I, JOHN KIRBY, Jr., a citizen of the United States, residing at Dayton, in the county of Montgomery and State of Ohio, 5 have invented certain new and useful Improvements in Lamps; and I do hereby declare that the following is a full, clear, and exact description of the invention.

My invention relates to car-lamps such as 10 are suspended from the roofs of railroad-cars, said lamps being composed in part of a rigid central frame and shade-holders for supporting shades above the burners, said shade-holders being independent of and not affected by 15 any movement of the oil-reservoir, and said lamps having downwardly-detachable reservoirs or oil-founts.

My said invention will be hereinafter fully 20 described with reference to the accompanying drawings, in which—

Figure 1 is a side elevation of a lamp embodying my improvements, the various parts of the same being seen in their normal or operative positions. Fig. 2 is a similar elevation 25 of the lower portion of said lamp, the oil-fount being shown separated, but not bodily detached from the central frame, and one of the chimneys being removed from the burner and hung upon the appropriate hook. Fig. 30 3 is a perspective view of the gravitating buffer detached from the lamp. Fig. 4 is a greatly-enlarged longitudinal section through one of the anti-rattling springs and its accessories. Fig. 5 is an enlarged vertical section through 35 the locking-ring and its accessories, said ring being shown engaged with one of the notched rods of the central frame, and a portion of the oil-fount and its surrounding shell or jacket being broken away. Fig. 6 is a horizontal 40 section of the central frame, taken directly above the anti-rattling springs. Fig. 7 is an enlarged axial section through the shade-holding device and its accessories. Fig. 8 is a similar section through the central frame and 45 the oil-fount, the latter being lowered from the former, but not detached therefrom. Fig. 9 shows one of the notched rods and a portion of the central frame. Fig. 10 is a plan of the annular lock-case, the cap-plate of the same 50 being detached therefrom. Fig. 11 is a plan

of said detached cap-plate. Fig. 12 is a perspective view of the lock-case, the cap-plate being removed therefrom and the oil-fount being separated from the central frame. Fig. 13 is an enlarged plan, showing one of the peripheral projections of the lock-ring engaged 55 with one of the notched rods, the latter being sectioned.

A represents the central frame, composed of a ring or annulus, which is preferably angular in transverse section, as more clearly shown in Fig. 8, and is provided with a series of outwardly-projecting screw-threaded shanks, *a*, for the attachment of hangers *B*, wherewith said frame is securely suspended 60 from the ceiling of a steamboat or car or other support. The horizontal web or flange of this ring is provided with a series of slots, *C*, (seen in Fig. 6,) which slots are furnished with plate-springs *c*, the free ends of which 65 latter bear upon the oil-fount or to a jacket or shell surrounding the same, for a purpose that will presently appear. Furthermore, this ring or central frame has a hook or equivalent supporting device, *D*, for each burner, a pair 70 of such hooks being shown in the drawings, although the invention is not limited to any precise number. Depending rigidly from this frame is a series of rods, *E*, each of which has 75 an upper notch or shoulder, *e*, and a lower notch or shoulder, *e'*. I preferably show four of these rods, but do not limit myself to any precise number, the peripheral projections *f* of a locking-ring, *F*, being adapted to engage either 80 with these upper or lower bearings, as occasion may require, said locking-ring being arranged to revolve within the annular lock-case *G*. Neck *g* fits into the central frame, 85 *A*, when the oil-fount is in its normal or elevated position.

Lock-case *G* is closed by an annular cap-plate, *I*, having openings *i* to admit the notched rods *E*, and other holes, *i'*, to receive screws that enter bearers *g'* of the case and thereby retain said cap-plate in its proper horizontal 95 position. Said plate serves to keep the ring *F* down to its proper seat in the case *G*, but it is not an essential element, as it may be omitted and other means employed to accomplish said result. The plate is more clearly seen in 100

Fig. 11. The bottom plate of this lock-case is pierced at J, which perforations are in line with the openings i of the cap I, so as to permit a ready passage of the notched rods, as seen in Fig. 5.

Ring F is preserved in its normal or locked position by a suitable spring or springs, four of such devices being seen in Figs. 10 and 12. These springs K are attached to pins k, projecting therefrom within the lock-case, the free ends of said springs being constantly in contact with suitable bearings, f', of said ring F, which latter is turned so as to disengage its projections f from the notched rods E by means of a knob or handle, L. This knob is chambered or bored out at l to admit a screw, M, around which latter is coiled a spiral spring, m, that forces said knob against the rim of the lock-case. Screw M is preferably tapped into a special projection, m', of the ring F, as seen in Fig. 10. This screw or stem traverses a horizontal slot, n, of a swell, N, of the lock-case, said swell having a shoulder, n', for a purpose that will presently appear. Swell N, shoulder n', movable knob L, and spring m may, however, be omitted without departing from the invention herein claimed. Springs K may also be omitted, which would necessitate the operator to press against the knob L or stem M to engage the ring F with the notched rods E. I prefer the use of the springs, which use makes such engagement automatic. Depending from the lock-case is a shell or jacket, O, from which project arms P P', that support burners p p' of any approved construction.

Shell O affords an air-space, Q, between it and the reservoir or oil-fount R, the latter having at bottom discharge-pipes r r', (seen only in Fig. 8,) the details of these devices O, P P', p p', and R r r' being more fully explained in my Patent No. 274,003. Reservoir R may have tubes S fitted within it for the passage of the rods E, as seen in Fig. 5, or these rods can traverse channels or grooves in said reservoir, as indicated by the dotted lines s in Fig. 8.

T is a drip pan or cup secured to the jacket O by a screw, t, engaging with a nut, t', which latter is soldered into the bottom of fount R. The upper end of this fount has a filling-nozzle, U, provided with a funnel, u, and screw-threaded plug u', the detachment of which latter enables the ready charging of said fount with oil or other burning-fluid.

V V' are the chimneys, and W W' the shades or globes, of the burners p p', said shades being suspended from domes w w', as seen in my Patent No. 314,251. Each dome is furnished with a gravitating buffer, the details of which are shown in Figs. 3 and 7, wherein X represents a cylindrical weight adapted to play freely within the dome, said weight having an axial bore, x. Y are grooves made longitudinally of the outer periphery of this weight, which grooves have springs y secured therein, the free ends of said springs being adapted to bear

against the interior of the dome, and thereby prevent rattling. Furthermore, the lower end of this weight has a concave cushion, Z, applied thereto, which latter is usually made of sheet metal, and is properly slotted at z to cause it to have a yielding or spring action. Cushion Z rests upon the lamp-chimney, and has a central opening, z', to allow the products of combustion to escape through the dome.

When my lamp is in its normal position, as seen in Figs. 1 and 5, the upper surface of lock-case G is in close contact with the under side of central frame, A, the springs c giving or bending sufficiently to permit this junction to take place, and yet preventing any rattling of said members A G by the vibrations of the boat or car. The case G, together with the attached shell O and its adjuncts, are securely held in this normal or elevated position by the engagement of the various peripheral projections f of the locking-ring F with the upper set of notches, e, of the rods E, said ring being maintained in this locked condition by the stress of springs K, as will be readily understood by reference to Fig. 10. Again, when the ring is in this locked position, spring m causes the knob L to snap in behind the shoulder n', and thus prevents any accidental movement of said ring, which latter, together with the rods and all of the other coupling devices, springs, &c., is concealed from sight.

Furthermore, in this coupled condition of the lamp the upper ends of the chimneys V V' are housed within the appropriate domes w w', and the gravitating buffers rest upon said chimneys, as clearly seen in Fig. 7. Reference to this illustration shows that the yielding plate Z rests directly upon the chimney, being held in this position by the weight X. Consequently the chimney is confined within the gallery of the burner with a yielding or elastic pressure that prevents breakage of said chimneys, no matter how violent the vibration of the car may be. This gravitating and yielding buffer also prevents the ascent of air around the sides of the chimney, which side currents cause the lamp to smoke and frequently to be extinguished.

When it is desired to trim the wicks or examine the burners, the knob L must first be grasped and then pulled outwardly, so as to disengage it from behind the shoulder n', after which act said knob is swung around to the position indicated by the dotted lines in Fig. 10, the result of this movement being to revolve the ring F far enough to liberate its projections f from the upper set of notches, e, of rods E. The lamp is then lowered until said projections are in line with the other set of notches, e', when knob L is liberated and the springs K are again allowed to exert their force.

Said springs accordingly produce a reverse revolution of ring F around the neck g, and thus compel the projections f of said ring to engage with the aforesaid set of lower notches, e'. The lamp is now securely locked in the position seen in Figs. 2 and 8, thereby

affording ample room for trimming the wicks, preparatory to which operation the chimney is detached from the burner and hung upon the hook D, as shown at V' in Fig. 2, the upper end of the chimney resting against the interior of dome w'. This arrangement will be especially advantageous with those lamps whose necks or domes are too small to admit the chimneys being raised high enough to be detached from the burners without taking down the entire reservoir or oil-fount. My chimneys can be thus suspended from their hooks when the reservoir requires filling, to accomplish which act the knob L is again disengaged from behind the shoulder n', and the ring F is turned to unlock the shell or jacket O from the notched rods. This shell is then lowered bodily, and the plug u' is unscrewed from the nozzle U, and the oil is poured directly into the funnel u, and flows from thence into the reservoir R, any spillage being collected in the drip-cups T. Plug u' is then screwed into the funnel, the pointed ends of rods E are inserted in the openings i of cap-plate I, so as to guide said rods into the tubes S, and the lamp is at once elevated and closely coupled to the central frame, A, as previously described.

The above is a description of the preferred construction of my lamp; but in some cases it may be found desirable to locate the locking-ring F within the central frame, A, and have the notched rods E project vertically from the reservoir R or jacket O. Again, in describing this preferred form of my invention I have alluded to certain devices seen in Patents Nos. 269,587, 274,003, 281,633, and 314,251, and on this account said devices are disclaimed from the present application. I also expressly disclaim the broad idea of interposing springs between coupled members to prevent rattling of the same, as this is known to be an old mechanical expedient. I further disclaim the broad idea of a lamp that is capable of being bodily detached from the supporting-frame, as such separable lamps with various forms of coupling devices are seen in a number of patents. I further disclaim the broad idea of a yielding holder applied to the top of a lamp-chimney for the purpose of retaining the latter in its proper place, as such holders are seen in several patents. Finally, I disclaim the devices shown and described in the following patents, to wit: Nos. 64,719, 189,063, 214,470, 244,407, 274,326, 307,044, 312,202, and 329,718.

I claim—

1. In a car-lamp having a central frame and shades held in holders rigidly secured above the burners, the combination of a downwardly-detachable oil-reservoir supported on rods depending from said frame and having an upper and lower set of notches, said reservoir being provided with a locking device that engages with either set of said notches and thereby couples said reservoir to said frame at different elevations, the reservoir be-

ing also provided with arms or branches that carry the burners, and passages for the supporting rods, substantially as herein described.

2. The combination, in a lamp, of a central frame, a downwardly-detachable oil-reservoir supported on a suitable number of notched rods, as E, depending from said frame, and a locking device that engages with said notches and thereby couples said frame to said reservoir, the said locking device being composed of case G, having slot n, apertures J, ring F, provided with projections, as f, stem M, and plate I, the reservoir being provided with suitable passages for the rods E and having arms or branches that carry the burners, substantially as herein described.

3. In a lamp, the central frame, A, provided with rods E, having notches e, an oil-reservoir having arms or branches which carry the burners, and passages for said rods E, in combination with a locking device to engage with said notches, composed of case G, having apertures J, swell N, and slot n, ring F, provided with projections f, stem M, knob L, and spring m, plate I, or its equivalent, springs K, pins k, and bearings f', the whole to operate substantially as herein described.

4. The combination, in a lamp, of a central frame, A, having a series of pendent rods, E, provided with upper notches, e, and lower notches, e', and a downward bodily-detachable oil-reservoir, R, provided with a locking-ring, F, having peripheral projections f, and an operating-knob, L, a spring or springs being employed for restoring said ring to its normal position, and said reservoir being furnished with branches or arms P P', which support the burners p p', as herein described.

5. The combination, in a lamp, of central frame, A, having a series of pendent rods, E, notched at e e', and a downward bodily-detachable oil-reservoir, R, provided with arms P P', burners p p', and a locking-ring, F, having peripheral projections f, a knob, L l, and a retracting-spring, K, the stem M, spring m, swell N, slot n, and shoulder n', for the purpose described.

6. In a lamp, the combination of a frame, A, slotted, as at C, plate-springs c, and a detachable reservoir, said springs arranged with their free ends interposed between said frame and reservoir, whereby rattling of these parts is prevented, substantially as herein described.

7. In a lamp having a detachable reservoir and shades held in holders rigidly secured above the burners, the combination of the frame A, to which frame or attachment thereto are secured chimney-supports, as D, whereby the lower end of the chimney may be supported on said frame when the reservoir and burners are disconnected from the frame, substantially as herein described.

8. The combination, in a lamp, of dome w and inclosed gravitating buffer X, having a

central passage, x , and at its lower end a yielding plate, Z , which plate is pierced at z' and rests upon the chimney located within said dome, for the purpose described.

- 5 9. A lamp-chimney buffer consisting of the channeled gravitating weight X x and slotted yielding plate Z z' , the sides of said weight being grooved at Y to admit springs y , in com-

bination with dome w or w' and their supporting bracket or brackets, for the purpose so described.
